[57] CLAIM

The ornamental design for a fingernail cuttings retainer, substantially as shown and described.

DESCRIPTION

FIG. 1 is a perspective view from the rear of a fingernail cuttings retainer, showing my new design;

FIG. 2 is a perspective view from the front thereof;

FIG. 3 is a bottom plan view thereof;

FIG. 4 is a side elevational view thereof;

FIG. 5 is a front end view thereof; and

FIG. 6 is a top plan view thereof.

The broken line showing a finger nail clipper in FIG. 4 is for illustrative purposes only and forms no part of the claimed design.
